POWER LUG STRAP RETAINER

William F. Leineweber, Jr., Greenville, S. C., assignor to W. D. Dodenhoff Company, Greenville, S. C., a corporation of South Carolina

Application November 26, 1948, Serial No. 62,145

23 Claims. (Cl. 139—154)

1

This invention relates to an improved power lug strap retainer or strap bracket for the picker stick of a loom.

As is well known, the shuttle-throwing motion of the picker stick of a conventional loom is generally imparted to the stick by a so-called power lug device, which constitutes a lug strap in the form of a loop of leather or canvas encircling the picker stick and a lug strap connected through suitable mechanism to a cam on the loom, so that periodically the lug stick is forcibly moved forward, at a very high acceleration, and thus the lug strap accelerates the picker stick inwardly at a high rate to accomplish the throwing of the shuttle to the other side of the loom.

Since the supporting linkage for most picker sticks has an effective pivot point near the bottom end of the stick, it is apparent that the vertical position at which the lug strap engages the picker stick will substantially affect the acceleration imparted to the picker stick. In fact, it often happens that a misadjustment of the vertical position of the lug strap relative to the picker stick of as little as one quarter of an inch can produce effects in the movement of the shuttle which will adversely affect the quality of cloth being woven.

By virtue of the very high forces acting upon the power lug device, it is necessary to replace lug straps at frequent intervals. Similarly, picker sticks are frequently replaced. Each time that a new lug strap or a picker stick is assembled to the loom, it is necessary to slightly adjust the vertical position of the lug strap with respect to the picker stick. To effect such adjustment, it has been customary heretofore to provide a lug strap clamp or bracket comprising a casting which was clamped to the picker stick in a desired position by a pair of U-bolts and cooperating nuts. Such an arrangement obviously was not susceptible of rapid adjustment, and since such adjustment could only be accomplished while the loom was shut down, all time consumed in effecting the adjustment adversely affected the rate of production of the loom. Since the lug strap requires replacement at frequent intervals, of the order of once every two or three weeks, it is apparent that the time required for adjustment of the vertical position of the lug strap clamp or bracket relative to the picker stick can be a substantial factor in obtaining optimum output from any particular loom.

Accordingly, it is an object of this invention to provide an improved lug strap clamp or bracket which may be assembled to a picker stick and adjusted thereon with a minimum amount of effort.

2

and time required for such operation, and which will maintain itself in any particular adjusted position on the picker stick, irrespective of the very high impact forces and vibration to which it is subjected during the normal operation of the loom.

Another object of this invention is to provide a power lug strap bracket which may be conveniently formed in its entirety as a metal stamping, and which may be rigidly secured to the picker stick in any selected position therealong without resuming the use of time-consuming fastening devices such as bolts, screws, or the like.

A particular object of this invention is to provide an improved power lug strap bracket for the picker stick of a loom, characterized by the employment of a spring-pressed wedge in cooperation with the bracket for effecting the rigid securing of the bracket to the picker stick in any selected position therealong.

Another object of this invention is to provide an improved mechanism for retaining a power lug strap clamp or bracket to the picker stick of a loom characterized by the employment of a pair of wedges disposed in the back-to-back relationship and urged into clamping engagement between the bracket and the picker stick by a common spring.

The specific nature of this invention as well as other objects and advantages thereof will become apparent to those skilled in the art from the following detailed description of the annexed sheet of drawings which, by way of preferred example only, illustrate one specific embodiment of the invention.

On the drawings:

Figure 1 is a schematic view illustrating the cooperation of the lug stick, a lug strap, and picker stick of a loom with a lug strap bracket constructed in accordance with this invention;

Figure 2 is an enlarged scale, side elevational view of the lug strap bracket embodying this invention, shown in assembled relationship with respect to the picker stick;

Figure 3 is a sectional view taken on the plane III—III of Figure 2;

Figure 4 is a perspective view of a modified form of wedge element to be employed in a lug strap bracket embodying this invention;

Figure 5 is a view similar to Figure 3, but illustrating the cooperation of the modified wedge with the sheet metal bracket constructed in accordance with the invention;

Figure 6 is an end elevational view of the

power lug strap bracket embodying one modification of this invention:

Figure 7 is a side elevational view of the structure shown in Figure 6;

Figure 8 is a cross-sectional view taken on line VIII—VIII of Figure 7;

Figure 9 is a cross-sectional view taken on line IX—IX of Figure 7.

As shown on the drawings:

Referring to Figure 1, the numeral 10 indicates a conventional lug stick connected to a lug strap 10a in the form of a loop of canvas or leather disposed in surrounding relationship to the intermediate portions of a picker stick 11. As is well known, periodically the lug stick 10 is pulled forcibly in the direction of its length by a suitable cam mechanism (not shown) and the closed end of the loop or lug strap 10a engages the picker stick 11 to pull the stick violently inwardly and thus effect the throwing of the shuttle across to the other side of the loom.

To insure the engagement of the power lug strap or loop 10a with the picker stick 11 at the proper vertical position on such picker stick, a lug strap clamp or bracket 12 is provided. According to this invention, the bracket 12 may be conveniently formed by stamping operations on sheet metal and is of generally U-shaped configuration, so constructed as to permit it to snugly straddle or envelop the picker stick 11 with the base portion 12a in engagement with the rear face 11a of the picker stick 11 and the arm portions 12b and 12c respectively projecting somewhat beyond the front face 11b of the picker stick 11.

To vertically position the lug strap 10a, the bracket 12 is provided with integral outwardly projecting wing portions 13 and 14 which project laterally from the top and bottom edges, respectively, of the arm portions 12b and 12c. The wing portions 13 and 14 are each of arcuate configuration so as to accommodate a limited tilting movement of the lug strap 10a relative to the bracket, which will occur in the normal operation of the picker stick 11.

To rigidly retain the bracket 12 in any selected adjusted position along the picker stick 11, this invention provides a pair of wedge members 15 operating between the free ends of arm portions 12b and 12c of the bracket 12 and the inner face 11b of the picker stick 11. The free end portions of the bracket arms 12a and 12b are each inturned and then reversely turned in such manner as to provide two pairs of guide ribs 16 and 17 (Figure 2) which are spaced from but facing the front face 11b of the picker stick 11, and which are oppositely inclined with respect to such front face. The wedge members 15 are of a wedge-shaped block construction, proportioned to permit their respective insertion into the triangular recess defined between the inturned free ends of the arm portions 12a and 12b of the bracket 12 and the front face 11b of the picker stick 11.

To facilitate the lateral guiding of the wedges 15, each wedge may be provided with a pair of spaced, parallel grooves 15a in its angular surface which respectively receive the guide ribs 16 or 17 as the case may be. The wedges 15 are assembled between the bracket 12 and picker stick 11 in back-to-back relationship and a common spring 18 is mounted therebetween so as to urge each of the wedges in a direction to effect a clamping engagement between the bracket 12 and the picker stick 11. Preferably, each wedge

block 15 is provided with a recess 15b in its large rear surface to provide a seat for the spring 18.

With the described construction, the bracket 12 may be readily slipped over the top end of the picker stick 11, or moved therealong to any desired position, merely by forcing the wedges 15 toward each other and thus compressing the spring 18. A particularly advantageous method of mounting the bracket on a stick already in operation is to spread the body at the open face and slip the bracket over the back of the stick near the top. Upon release of the wedges 15, the spring 18 urges each wedge into snug engagement between the picker stick 11 and the inclined guide surfaces 16 and 17 provided by the inturned free ends of the bracket arms 12b and 12c. Any tendency of the bracket 12 to move upwardly relative to the picker stick 11 is resisted by one wedge, while the other wedge equally resists any tendency of the bracket 12 to shift downwardly relative to the picker stick 11. The repeated blows imparted to the bracket 12 by the lug stick 10, as well as vibration, only have the effect of further securing the tightness of engagement of the wedge element 15, since the spring 18 immediately takes up any looseness that may be produced between the bracket, the picker stick and the wedge. Hence the bracket 12 may not only be conveniently positioned at any desired vertical position along the picker stick 11, but will be rigidly retained in such adjusted position.

Referring to Figures 4 and 5, a modification of this invention is shown wherein the wedge elements 20 are formed as sheet metal stampings rather than as solid block-like members. Such wedge elements comprise a base portion 20a, parallel side wall portions 20b and 20c, respectively, and an end wall portion 20d. The side wall portions 20b and 20c have generally inclined top surfaces 20e which may be of slightly arcuate configuration for a purpose that will be hereinafter explained.

The wedge element 20 may then be snugly mounted between the bracket 12 and the picker stick 11 by the insertion of the side wall portions 20b and 20c respectively into the spaces defined between the reversely turned guide ribs 16 and 17 and their respective side wall portions 12b and 12c, in the manner best shown in Figure 5. In this modification, the end wall surface 20d of the wedge element 20 functions as a seat for the spring 18 and again, a common spring is employed to urge both of the wedge elements 20 toward their clamping positions between the bracket 12 and picker stick 11.

In both modifications of this invention, the surface of the wedge element adjacent the picker stick may be knurled or serrated as indicated at 20g in Figure 4 to increase the securement of engagement with the front face 11b of the picker stick 11.

Also, in both modifications of this invention it may be desirable to form one of the cooperating wedging surfaces of the bracket 12 and the wedge elements 15 or 20, as the case may be, with a slightly arcuate configuration so as to permit the wedge to more readily accommodate itself to variations in dimensions or configuration of the picker stick 11. As is well known, picker sticks vary substantially in dimensions and very often the rear face 11a of the picker stick may not be exactly parallel with the front face 11b. By providing the inclined surface of the wedge element 75 with an arcuate configuration as indicated at 20e

in Figure 4, or, alternatively, by forming the wedging surfaces 16 and 17 on the bracket 12 of slightly convex configuration, such variations in dimensions or configuration of the picker stick 11 may be conveniently accommodated without adversely affecting the securement of attachment of the bracket 12 thereto.

A further modification is shown in Figures 6, 7, 8 and 9 wherein an adjustable wedge element assembly is shown comprising a wedge element 25 and a locking wedge 26.

The wedge element 25 is provided with a base portion 25a, the surface of which may be conditioned for frictional engagement with the picker stick, parallel side wall portions 25b and 25c respectively, and an end wall portion 25d. It will be noted that the end wall portion 25d is provided with a shallow depression suitable for receiving an object in rotatable bearing engagement therewith.

The locking wedge 26 is provided with a base portion 26a, which also may be conditioned upon its engaging surface, parallel side wall portions 26b and 26c, respectively, and an end wall portion 26d. The end wall portion 26d is provided with an inwardly extending boss and may be suitably drilled and tapped as at 27 to receive a filister head adjusting screw 28, or the like, in threaded engagement therewith.

Thus, it should be evident that the wedge elements 25 and 26 may be snugly mounted between the bracket 12 and the picker stick 11 by insertion of the side wall portions 25b, 25c and 26b, 26c, respectively, into the spaces defined between the reversely turned guide ribs 16 and 17 and their respective side wall portions 12b and 12c, in the manner best shown in Figure 5.

In this modification the depressed end portion 25d of the wedge element 25 functions as a seat for the adjusting screw 28 and the wedge element 25 is urged apart from the locking wedge 26 and toward a locking position by selective adjustment of the adjusting screw 28. A fiber lock washer 29 may be provided, as shown in Figure 7, for the purpose of locking the setting made with the adjusting screw 28 against vibration.

Obviously, with a power lug strap bracket construction as described, the time required for removing such bracket from the picker stick 11, or adjusting the vertical position of the bracket on the picker stick 11, may be maintained at a minimum, and hence the shutdown time of the loom required to effect such adjustment may be substantially reduced. Furthermore, all of the components of the described construction may be economically manufactured by low cost, high production methods.

It will, of course, be understood that various details of construction may be modified through a wide range without departing from the principles of this invention, and it is, therefore, not the purpose to limit the patent granted hereon otherwise than necessitated by the scope of the appended claims.

I claim as my invention:

1. A power lug strap retainer for a picker stick comprising, in combination, a bracket defining a channel constructed to envelop a picker stick, means on the outer faces of said bracket for vertically retaining a lug strap in engagement therewith, said bracket having an inclined, inwardly facing surface portion spaced from one face of a picker stick positioned therein, a wedge having its angularly disposed surfaces respectively engageable with said inclined surface por-

tion of the bracket and said one face of the inserted picker stick, and means urging said wedge into clamping engagement between said bracket and the picker stick.

5. 2. A power lug strap retainer for a picker stick comprising, in combination, a bracket defining a channel constructed to envelop a picker stick, means on the outer faces of said bracket for vertically retaining a lug strap in engagement therewith, said bracket having a pair of adjacent, inwardly facing, oppositely inclined surface portions spaced from one face of a picker stick positioned therein, a pair of wedges, each having its angularly disposed surfaces respectively engageable between one of said inclined surface portions and said one face of an inserted picker stick, and means urging said wedges toward clamping position between said bracket and the picker stick.
- 10 3. The combination defined in claim 2 wherein said wedges each comprise a solid, wedge-shaped member having a groove on its angular surface for reception of said angularly disposed bracket surface.
- 15 4. The combination defined in claim 2 wherein said wedges each comprise a stamping having a base portion, opposed side wall portions, and an end wall portion, said side wall portions having their top surfaces arcuately formed in a wedge-like configuration to cooperate with said angularly disposed bracket surfaces.
- 20 5. A power lug strap retainer for a picker stick comprising a sheet metal bracket of U-shaped configuration adapted to straddle a picker stick, the arm portions on said bracket extending laterally beyond the picker stick to retain a lug strap, the free ends of said bracket being inturned to provide inclined surfaces spaced from and facing one side of the straddled picker stick, a wedge member disposed between said inturned free ends and said one side of the picker stick with the inclined faces of said wedge respectively engaging said inturned free ends and said one side of the straddled picker stick, and resilient means urging said wedge in the direction to increase its wedging action.
- 25 6. The combination defined in claim 5 wherein said wedge comprises a solid wedge-shaped member having a pair of parallel grooves on its angular surface, said inturned free ends of said bracket being turned sufficiently to assume a reversed configuration and define tracks cooperating with said grooves to guide said wedge in its movement relative to the bracket.
- 30 7. A power lug strap retainer for a picker stick comprising a sheet metal bracket of U-shaped configuration adapted to straddle a picker stick, the arm portions of said bracket extending laterally beyond the picker stick and the free ends thereof being inturned, each of said inturned end portions defining oppositely inclined surfaces spaced from and facing one side of the straddled picker stick, a pair of wedges respectively disposed between said oppositely inclined surfaces and said one side of the straddled picker stick, and a common spring urging said wedges into clamping engagement between said bracket and said straddled picker stick.
- 35 8. The combination defined in claim 7 wherein said wedges each comprise a solid, wedge-shaped member having a groove in its angular surface for reception of one of said oppositely inclined ramp surfaces, and having a recess in the large end face thereof to provide a seat for one end of said common spring.
- 40 9. The combination defined in claim 7 wherein said wedges each comprise a stamping having a base portion, opposed side wall portions, and an end wall portion, the side wall portions having their top surfaces arcuately formed in a wedge-like configuration to cooperate with said angularly disposed bracket surfaces.
- 45 10. The combination defined in claim 7 wherein said wedges each comprise a stamping having a base portion, opposed side wall portions, and an end wall portion, the side wall portions having their top surfaces arcuately formed in a wedge-like configuration to cooperate with said angularly disposed bracket surfaces.
- 50 11. The combination defined in claim 7 wherein said wedges each comprise a stamping having a base portion, opposed side wall portions, and an end wall portion, the side wall portions having their top surfaces arcuately formed in a wedge-like configuration to cooperate with said angularly disposed bracket surfaces.
- 55 12. The combination defined in claim 7 wherein said wedges each comprise a stamping having a base portion, opposed side wall portions, and an end wall portion, the side wall portions having their top surfaces arcuately formed in a wedge-like configuration to cooperate with said angularly disposed bracket surfaces.
- 60 13. The combination defined in claim 7 wherein said wedges each comprise a stamping having a base portion, opposed side wall portions, and an end wall portion, the side wall portions having their top surfaces arcuately formed in a wedge-like configuration to cooperate with said angularly disposed bracket surfaces.
- 65 14. The combination defined in claim 7 wherein said wedges each comprise a stamping having a base portion, opposed side wall portions, and an end wall portion, the side wall portions having their top surfaces arcuately formed in a wedge-like configuration to cooperate with said angularly disposed bracket surfaces.
- 70 15. The combination defined in claim 7 wherein said wedges each comprise a stamping having a base portion, opposed side wall portions, and an end wall portion, the side wall portions having their top surfaces arcuately formed in a wedge-like configuration to cooperate with said angularly disposed bracket surfaces.
- 75 16. The combination defined in claim 7 wherein said wedges each comprise a stamping having a base portion, opposed side wall portions, and an end wall portion, the side wall portions having their top surfaces arcuately formed in a wedge-like configuration to cooperate with said angularly disposed bracket surfaces.

9. The combination defined in claim 7 wherein said wedges each comprise a stamping having a base portion, opposed side wall portions, an end wall portion, said side wall portions having their top surfaces arcuately formed in a wedge-like configuration to cooperate with said oppositely inclined ramp surfaces, and said end wall portion being constructed and arranged to provide a seat for one end of said common spring.

10. A power lug strap retainer for a picker stick comprising a sheet metal bracket of U-shaped configuration adapted to straddle a picker stick, the arm portions of said bracket extending laterally beyond the straddled picker stick and the free ends thereof being reversely bent to provide guide surfaces spaced from one face of the straddled picker stick and inclined relative thereto, a wedge disposed intermediate said guide surfaces and said one face of the straddled picker stick, means on said wedge cooperating with said guide surfaces to limit lateral movements of said wedge, and means urging said wedge into clamping engagement between said bracket and the straddled picker stick.

11. The combination defined in claim 10 wherein in said wedge comprises a solid block having parallel grooves in its angular surface respectively receiving said free ends of said bracket.

12. The combination defined in claim 10 wherein in said wedge comprises a generally U-shaped stamping having upstanding side wall portions of generally angular configuration and respectively engageable between said free end portions and said arm portions of said bracket.

13. A power lug strap retainer for a picker stick, comprising a sheet metal bracket adapted to straddle a picker stick, integral wing portions on the exterior of said bracket for vertically retaining a lug strap spring-pressed, and a spring-pressed wedge disposed between said bracket and the straddled picker stick for clamping said bracket to said straddled picker stick.

14. The combination defined in claim 13 wherein in one of the cooperating surfaces of said wedge and said bracket is arcuately shaped.

15. A power lug strap retainer for a picker stick comprising a sheet metal bracket adapted to straddle a picker stick, a pair of oppositely acting wedges disposed between said bracket and the straddled picker stick in back-to-back relationship, and means urging said wedges to a clamping position.

16. The combination defined in claim 15 wherein in said wedges each comprise a solid, wedge-shaped member having a groove in its angular surface for reception of said angularly disposed bracket surface.

17. A power lug strap retainer for a picker stick comprising, in combination, a bracket defining a channel constructed to envelop a picker stick, means on the outer faces of said bracket for vertically retaining a lug strap in engagement therewith, said bracket having an inclined, inwardly facing surface portion spaced from one face of the picker stick, a wedge having its angularly disposed surfaces respectively engageable with said inclined surface portion of the bracket and said one face of the picker stick, and adjustable means for selectively urging said wedge into clamping engagement between said bracket and the picker stick.

18. A power lug strap retainer for a picker stick comprising, in combination, a bracket defining a channel constructed to envelop a picker stick, means on the outer faces of said bracket

for vertically retaining a lug strap in engagement therewith, said bracket having a pair of adjacent, inwardly facing, oppositely inclined surface portions spaced from one face of the picker stick, a pair of wedges, each having its angularly disposed surfaces respectively engageable between ones of said inclined surface portions and said one face of the picker stick, and an adjusting screw threadedly carried by one of said wedges selectively adjustable to urge said wedges toward clamping position between said bracket and the picker stick.

19. A power lug strap retainer for a picker stick comprising a sheet metal bracket adapted to straddle a picker stick, a pair of oppositely acting wedges disposed between said bracket and the straddled picker stick in back-to-back relationship, and an adjusting screw threadedly carried by one of said wedges for urging said wedges to a clamping position.

20. A power lug strap retainer for a picker stick comprising a sheet metal bracket adapted to straddle a picker stick, a pair of oppositely acting wedges disposed between said bracket and the straddled picker stick in back-to-back relationship, and an adjusting screw threadedly carried by one of said wedges for urging said wedges to a clamping position, the other of said wedges having a recess in the large end face thereof to provide a seat for bearing engagement with said adjusting screw.

21. A power lug strap retainer for a picker stick comprising a sheet metal bracket of U-shape configuration adapted to straddle a picker stick, the arm portions of said bracket extending laterally beyond the picker stick to retain a lug strap and the free ends thereof being inturned, each of said inturned end portions defining oppositely inclined surfaces spaced from and facing one side of the straddled picker stick, a pair of wedges respectively disposed between said oppositely inclined surfaces and said one side of the straddled picker stick, each of said wedges comprising a stamping having a base portion, opposed side wall portions, and end wall portion, said side wall portions having their top surfaces curvedly formed in a wedge-like configuration to cooperate with said oppositely inclined surfaces, and adjustable screw means cooperable with said wedges to move same into clamping engagement between said bracket and said straddled picker stick.

22. A power lug strap retainer for assembly on the picker stick of a loom comprising, a generally U-shaped bracket having winged lug strap positioning projections extending laterally therefrom and adapted to envelop a picker stick with the free ends of the arm portions of the bracket extending beyond one face of the picker stick and shaped to position locking elements therebetween, the locking elements including wedge means positioned by the bracket arm portions against the said one face of the picker stick and means cooperable with the wedge means to urge said wedge means into locking relationship with the bracket and the picker stick, whereby said retainer may be selectively and adjustably positioned vertically on the picker stick.

23. A power lug strap retainer for assembly on the picker stick of a loom comprising, a generally U-shaped bracket having winged lug strap positioning projections extending laterally therefrom and adapted to envelop a picker stick with the free ends of the arm portions of the bracket extending beyond one face of the picker stick

and being shaped to position locking elements therebetween, the locking elements including a first wedge defining a threaded aperture in the large end face thereof, a screw threadededly carried thereby, a lock washer carried by said screw and cooperable with said first wedge to retain said screw in selected adjusted positions and a second wedge defining a recess in the large end face thereof to provide a seat for the screw, said first and second wedges being positioned against the said one face of the picker stick by the bracket arm portions for effecting selective vertical positioning of the lug strap retainer thereon, said screw operable to urge said wedges into clamping engagement between the bracket and the picker 15 stick.
